TWO-STAGE PROCESS FOR THE CATALYTIC REFORMING OF GASOLINE

Vladimir Haensel, Hinsdale, Ill., assignor to Universal Oil Products Company, Chicago, Ill., a corporation of Delaware

Application May 12, 1949, Serial No. 92,866

3 Claims. (Cl. 196—50)

1

This application is a continuation-in-part of copending application Serial No. 788,673, filed November 28, 1947, now U. S. Patent No. 2,479,110.

This invention relates to a reforming process and more particularly to a combination of mutually related and interdependent steps for the reforming of gasoline or fractions thereof.

The term "reforming" is well known in the petroleum industry and refers to the treatment of gasoline or fractions thereof to improve the anti-knock characteristics. In the interest of simplicity, reference to "gasoline" in the present specification and claims shall mean either a full boiling range gasoline or any selected fraction thereof. In general, when a selected fraction is subjected to reforming, it usually comprises a higher boiling fraction, commonly referred to as naphtha, and generally having an initial boiling point of above about 150° F. and an end boiling point of below about 425° F.

The present invention is applicable to the reforming of any gasoline and is particularly useful in the improvement of gasolines of low octane number, including straight run gasoline, natural gasoline, etc.

The reforming process involves many reactions. The primary reactions comprise controlled or selective cracking and aromatization, the latter including dehydrogenation of C₆ naphthenic hydrocarbons to aromatics and the cyclization of straight chain or mildly branched chain aliphatic hydrocarbons of more than 6 carbon atoms to form aromatics. Other reactions occurring during reforming include isomerization, both of aliphatic hydrocarbons and of naphthenic hydrocarbons containing 5 and 6 carbon atoms in the ring, hydrogen transfer reactions, alkyl transfer reaction, etc.

As hereinbefore set forth, one of the primary reactions in reforming is controlled or selective cracking. This cracking is preferably effected in the presence of hydrogen and, therefore, is known as "hydrocracking." The hydrocracking must be controlled in quantity so as not to produce an excessive amount of normally gaseous products, which represent a loss of desirable gasoline components, and also the cracking must not be excessive in order that the amount of carbonaceous deposit, hereinafter referred to as carbon, is not excessive. The carbon formation, not only means a further loss of components from the desired gasoline, but also means deactivation of the catalyst due to the deposition of carbon thereon. Further, the cracking must be controlled in quality and must not result in the

2

formation of excessive smaller molecules such as methane, ethane, propane and butane, but instead should comprise the production of molecules of the nature of pentane, hexane, heptane, benzene, toluene, etc. This controlled or selective cracking results in a gasoline of higher volatility and of higher octane number.

The hydrocracking reaction is best effected at conditions different from those best for the aromatization reaction. These conditions differ both as to temperature, pressure and space velocity, as well as in catalyst. The space velocity is defined as the weight of oil per hour per weight of catalyst in the reaction zone. The present invention provides for effecting each of these reactions in separate zones under separately controlled conditions and in the presence of different catalysts.

In one embodiment the present invention relates to a process for reforming gasoline which comprises subjecting said gasoline to conversion at hydrocracking conditions in the presence of a hydrocracking catalyst and then to conversion at aromatizing conditions in the presence of an aromatizing catalyst, each of said conversions being effected under separately controlled conditions.

In a specific embodiment the present invention relates to a process for reforming gasoline which comprises subjecting said gasoline to contact at hydrocracking conditions with a catalyst comprising alumina, from about 0.01% to about 1% by weight of platinum and from about 0.1% to about 8% by weight of halogen combined with at least one of said alumina and platinum, and thereafter subjecting said gasoline to contact at aromatizing conditions with a catalyst comprising alumina and from about 0.01% to about 1% by weight of platinum.

As hereinbefore set forth, gasoline is subjected to hydrocracking in the first step of the process. Any suitable catalyst which serves to effect the hydrocracking reaction as the primary reaction in this step of the process may be employed within the scope of the present invention. A preferred catalyst comprises alumina, from about 0.01% to about 1% by weight of platinum and from about 0.1% to about 8% by weight of a halogen. When the halogen comprises fluorine, it is preferably present in an amount of from about 0.1% to about 3% by weight and, when the halogen comprises chlorine, it is preferably present in an amount of from about 0.2% to about 8% by weight of the catalyst. It is understood that the halogen may comprise a mixture of these two

halogens or the other halogens, bromine and iodine, alone or in combination with the fluorine and/or bromine, the total amount of halogen being within the range of from about 0.1% to about 8% by weight of the catalyst.

Other suitable but not necessarily equivalent catalysts for use in the hydrocracking step of the process comprises a cracking component, such as silica-alumina, silica-zirconia, silica-magnesia, silica-thoria, silica-vanadia, silica-alumina-zirconia, silica-alumina-magnesia, silica-alumina-thoria, silica-alumina-vanadia, alumina-boria, etc. compositos with a minor proportion and generally from about 0.01% to about 10% of a metal such as platinum, palladium, nickel, cobalt, etc.

The conditions in the hydrocracking step of the process will vary with the particular charging stock, catalyst, etc., but, in general, will be within the range of from about 600° to about 1000° F., a pressure of from about 500 to 1200 pounds, or more, a weight hourly space velocity of from about 0.2 to about 5, and a hydrogen to hydrocarbon ratio of from about 2 to 10 or more mols of hydrogen per mol of hydrocarbon.

As compared to the aromatization reaction, the hydrocracking reaction is generally favored at lower temperatures, higher pressures and lower space velocities. In general, it is also desired to have a higher concentration of hydrogen in the hydrocracking reaction than in the aromatization reaction. The use of a higher pressure in the hydrocracking reaction offers the added advantage that the pressure therein is sufficient to transfer the reactants from the first step of the process to the second step without the necessity of intervening means to increase pressure between stages.

Any suitable catalyst may be employed in the aromatization step of the process. A particularly preferred catalyst comprises alumina and from about 0.01% to about 1% by weight of platinum. This catalyst is a particularly effective aromatization catalyst. In another embodiment of the invention the alumina-platinum for use in the aromatization step of the process may contain a halogen combined therewith, but the amount of halogen in this case is less than the amount of halogen contained in the hydrocracking catalyst. Other suitable but not necessarily equivalent aromatization catalysts include alumina-chromia, alumina-molybdena, etc.

The aromatization reaction is preferably effected at a temperature within the range of from about 800° to about 1100° F., a pressure from about 50 to about 700 pounds per square inch, a weight hourly space velocity of from about 2 to about 20, and a hydrogen to hydrocarbon ratio of from about 1 to about 6 mols of hydrogen per mol of hydrocarbon.

The conditions hereinbefore set forth are preferred for effecting each of these reactions separately. Even under these preferred conditions, some aromatization will occur during hydrocracking and similarly some hydrocracking will occur during aromatization. However, the conditions hereinbefore set forth are preferred for minimizing the amount of side reactions. However, in another embodiment of the invention it may be advantageous to effect a portion of the dehydrogenation during the hydrocracking reaction and, in accordance with this embodiment of the invention, the conditions of operation in the hydrocracking step of the process may be modified accordingly. For example, it may be

advantageous to utilize a slightly higher temperature and probably a lower pressure. The advantage of effecting a portion of the dehydrogenation during the hydrocracking is particularly related to the isomerization of the naphthenes in the feed. Along with isomerization of 5 carbon atom rings to 6 carbon atom rings and subsequent dehydrogenation to aromatics in the later step of the process, C₆ naphthenes contained in the charge will isomerize to C₅ naphthenic rings. The C₅ naphthenic rings cannot be dehydrogenated to aromatics and, therefore, by dehydrogenating some of the C₆ naphthenic rings to aromatics, the isomerization thereof to C₅ rings is avoided.

A particular advantage for effecting the hydrocracking prior to dehydrogenation is that the larger molecules present in the charge, at least in part, are converted to smaller molecules and thereby are prevented from forming aromatics containing more than one ring per molecule such as naphthalene, anthracene, etc. The polycyclic aromatics appear to be responsible for the formation of carbon during the reforming process and, by preventing their formation, the amount of carbon formed in the process will be reduced.

The novelty and utility of the present invention is further illustrated in the accompanying diagrammatic flow drawing which illustrates several specific embodiments of the present invention.

As hereinbefore set forth, the gasoline charge to the process may comprise a full boiling range gasoline or any selected fraction thereof. When the gasoline comprises a selected fraction, the remaining components of the gasoline may be blended with the final reformat as, for example, by fractionating a full boiling range gasoline to separate a light fraction and a heavy fraction.

The heavy fraction is charged to the process of the present invention and the light fraction is subsequently blended with the product of the process.

In the interest of simplicity, pumps, compressors, valves and similar appurtenances have

been omitted from the drawing. These are well

known and need not be illustrated or described in detail.

Referring to the drawing, the gasoline charge is directed through lines 1 and 2 to heater 3 wherein it is raised to the desired temperature and then is directed through line 4 into hydrocracking reactor 5. When desired, all or a portion of the charging stock may be directed through line 6, into and through heat exchanger 7, and then through lines 8, 1 and 2 to heater 3 as aforesaid. The purpose of this heat exchange will be hereinafter described.

A suitable hydrocracking catalyst is deposited in reactor 5 and the gasoline along with hydrogen, recycled within the process in a manner to be hereinafter set forth, is passed therethrough in either downward flow as illustrated or upward flow not illustrated. In the case here illustrated, the catalyst is deposited as a fixed bed in reactor 5 but it is understood that the process may be effected in the fluidized type of operation in which the catalyst and hydrocarbons are maintained in a state of turbulence under hindered settling conditions, the moving bed type of process in which the catalyst and hydrocarbons are passed in either concurrent or counter-current flow, the suspensoid type of operation in which the catalyst and hydrocarbons are passed as a slurry through the reaction zone or in any

other suitable manner of intimately contacting the reactants with the catalyst.

The hydrocracked products are withdrawn from zone 5 through line 9 and are reheated in heater 10 to the desired temperature as hereinbefore set forth, and then are directed through line 11 to aromatization reactor 12, along with hydrogen recycled within the process in the manner to be hereinafter set forth. Any suitable method of intimately contacting the reactants with the catalyst may be employed. In the case here illustrated the reactor is packed with an aromatization catalyst and the products are passed therethrough.

The effluent products from aromatization zone 12 are withdrawn through line 13 and preferably are heat exchanged in exchanger 1 with all or a portion of the gasoline charged to the process in order to thereby partially cool the aromatization products and to preheat the incoming gasoline charge. The aromatization products are then directed through line 14 and preferably are cooled further in cooler 15. The cooled products are then directed through line 16 to receiver 17 wherein hydrogen is separated from liquid products, the hydrogen being withdrawn through line 18. When desired, the hydrogen may be heated in a separate heating zone, not illustrated, and then recycled by way of lines 19, 20 and 11 to reactor 12 and/or through lines 19, 21 and 4 to reactor 5. When a separate heating zone is not utilized for the hydrogen, the recycled hydrogen, when desired, may be directed through lines 19 and 22 through heater 10 and then to reactor 12 or through lines 19 and 1 through heater 3 and then to reactor 5. The distribution of hydrogen to reactors 5 and 12 will be controlled to maintain the desired hydrogen concentration in each of these reactors. Preferably a greater hydrogen concentration is maintained in reactor 5 than in reactor 12 as hereinbefore set forth. In another embodiment, all of the hydrogen may be recycled to reactor 5 and thereafter carried into reactor 12. When the supply of hydrogen in the process is not sufficient, additional hydrogen may be introduced from an extraneous source through line 23. On the other hand, when the amount of hydrogen produced in the process is in excess of that desired, the excess hydrogen may be removed from the process by way of line 23.

The condensate in receiver 17, comprising gasoline and hydrocarbon gases, is withdrawn from receiver 17 through line 24 for subsequent separation and recovery. Usually this separation will include stabilization of the gasoline to produce a final gasoline of desired vapor pressure and to thereby separate normally gaseous products. As hereinbefore set forth, by effecting these reactions in separate reactors, the amount of normally gaseous products is lower than would be obtained by effecting both of these reactions in a single reaction zone.

The amount of carbon formed on the catalyst will be lower in the process of the present invention than by effecting these reactions in a single zone. However, in general, the amount of carbon in the hydrocracking reaction will be more than in the aromatization reaction. The catalyst may be regenerated in any suitable manner such as by burning the carbon therefrom in the presence of air or other oxygen containing gas at

temperatures of from about 600° to 1000° F. or more.

The following example is introduced to illustrate further the novelty and utility of the present invention but not with the intention of unduly limiting the same.

Example

A Mid-Continent naphtha with a boiling range of 182-402° F. and having a clear motor method octane number of 34.6 and a research octane number of 34.8 was processed over a catalyst consisting of 0.1% platinum and 3% fluorine on alumina at 743° F., 500 pounds per square inch, 2.5 space velocity and at a hydrogen to hydrocarbon ratio of 3 to 1. The reformate from this first step had a clear octane number of 68.7 (motor method) and 72.2 (research method), and was obtained in a yield of 100.6% by volume. This reformate was then processed over a catalyst containing 0.3% platinum and no fluorine, the remainder being alumina, at 850° F. catalyst temperature, 500 pounds per square inch, 3 to 1 hydrogen to hydrocarbon ratio and 2 space velocity. The reformate obtained in a yield of 93.7% by volume had a clear motor method octane number of 76.6 and a clear research octane number of 83.4.

I claim as my invention:

1. A process for reforming gasoline which comprises subjecting said gasoline to conversion at a temperature of from about 600° to about 1000° F., a pressure of from about 500 to about 1200 pounds per square inch, a weight hourly space velocity of from about 0.2 to about 5 and a hydrogen to hydrocarbon ratio of from about 2 to about 10 mols of hydrogen per mol of hydrocarbon in the presence of a catalyst comprising alumina, platinum in an amount of from about 0.01% to about 1% by weight and a halogen combined therewith in an amount of from about 0.1% to about 8% by weight, and thereafter subjecting said gasoline to conversion at a higher temperature in the range of from about 800 to about 1100° F., a lower pressure in the range of from about 50 to about 700 pounds per square inch, a higher weight hourly space velocity in the range of from about 2 to about 20 and a hydrogen to hydrocarbon ratio of from about 1 to about 6 mols per mol of hydrocarbon in the presence of a catalyst comprising alumina and from about 0.01% to about 1% by weight of platinum.
2. The process of claim 1 further characterized in that said halogen comprises chlorine.
3. The process of claim 1 further characterized in that said halogen comprises fluorine.

VLADIMIR HAENSEL.
